UNITED STATES PATENT OFFICE.

JAMES S. CONWELL AND HOMER E. HITTLE, OF LOS ANGELES, CALIFORNIA.

HEATER FOR GASEOUS FUEL.

1,124,706.

Specification of Letters Patent. Patented Jan. 12, 1915.

Application filed June 29, 1913. Serial No. 708,547.

To all whom it may concern:

Be it known that we, JAMES S. CONWELL and HOMER E. HITTLE, both citizens of the United States, residing at Los Angeles, in the county of Los Angeles and State of California, have invented new and useful Improvements in Heaters for Gaseous Fuel, of which the following is a specification.

This invention relates to heaters for gases from carburetors and more especially to heat gaseous mixtures from carburetors designed for vaporizing heavy hydrocarbons, and the principal object is to provide a gaseous mixture heater that may be readily interposed 15 between a carburetor and the engine intake.

It is a further object to provide an auxiliary heater intermediate carburetors and their engines having a maximum amount of heat radiating surface to a minimum heat 20 conveying means.

It is a further object to provide means for assembling a plurality of flanged rings on a tubular structure inclosed within a return bend casing.

In the drawings accompanying this specification and forming therewith the application for Letters Patent: Figure 1 is a plan view of the heater. Fig. 2 is a longitudinal section through the heater, the flanged tube 25 being shown partly in elevation and partly in section. Fig. 3 is a side elevation of the heater, as shown in Fig. 1 with the base connecting the heater to the exhaust pipe of the engine. Fig. 4 is an elevation of the 25 end connected to the exhaust. Fig. 5 is a section on the line 5—5 of Fig. 2, viewed in the direction indicated by the arrows, clearly showing the deflector cone mounted in the heater. Fig. 6 is a detail perspective of the 40 flanged ring.

This invention is adapted to be interposed between the carburetor 7 and the intake manifold 8 secured to an internal combustion engine, and consists mainly of a flat tubular casing 9, preferably cast of metal, and having end flanges or ears 10 and 11 to which may be secured the closing sections 12 and 14, respectively. A cross section of the casing, as clearly shown in Fig. 6, provides an elliptically formed interior, the casing 9 having an end wall 15 through which are formed a plurality of bores shown as a pair in horizontal line in which are supported the ends of the tubes 16 and 17. Intermediate the flanged end 11 of the outwardly disposed end and the closure 14 a

plate 18 is also provided with a pair of bores which register with those in the end wall 15 and adapted to form an end bearing and also rigid support for the tubes 16 and 17.

Previous to assembling the tubes within the casing 9 a plurality of flanged rings 20 are assembled on each of the tubes, their edges slitting, as clearly shown in Fig. 2, a sufficient number being applied to cover the entire peripheral surface of the tubes supported between the wall 15 and the plate 18, the radiating surface from these tubes being greatly increased by these means.

The upper and lower surfaces of the casing 9 are provided with flange surfaces 21 and 22 to which the flanges of the intake and carburetor are respectively secured by suitable fastenings 23 and 24, openings being formed in these flanged portions of the casing to register with the opening in the devices to which they are connected so that the gases mixed in the carburetor are drawn through the heater into contact with the radiating surfaces formed by the flanged rings 20. To assist in the distribution of the gases and insure their more intimate contact with a greater number of the flanges 25 of the rings 20 a baffle plate or plates 26 are provided, which rests upon the upper portion of the flanges 25 and on the lower face of the casing 9 and is of the tapered conical cross section shown in Fig. 5, with the openings 27 arranged concentrically with the intake opening, the ends 28 of these plates being extended as shown in Fig. 1.

The closure 12 is of the common return bend form or cap so that the gases conveyed through the pipe 17 will be deflected and carried back through the pipe 16, the oppositely disposed closure 14 being provided with two sockets having openings which register with the internal tubes 16 and 17, these sockets being split at their upper outer edges provided with ears 29 and 30 through which are carried screws 31 and 32, respectively, so that these sockets may be constricted and clamp the pipe elbows 33 and 34, the pipe 34 being connected to the exhaust of the engine and the pipe 33 leading to the muffler or return to the exhaust line depending on the amount of exhaust it is desired to carry through the heater.

The operation of the device will be readily understood from the above description, the exhaust gases being carried through the heater and segregated, the flanged rings ab-

sorbing and distributing a large amount of the heat ordinarily lost, which in turn is absorbed by the mixtures being drawn through the carbureter and intake, the baffle plate distributing and causing a more intimate mixture of the mixed gases in the heater and forcing them to absorb the heat radiated from the heated flanges.

What we claim is:

- 10 1. A gaseous mixture heater, comprising an elongated flattened casing having a plurality of orifices, means to connect a pair of oppositely disposed orifices intermediate the carbureter and the intake manifold of an internal combustion engine, a plurality of flanged tubes supported in registering and oppositely disposed orifices in said casing, means to direct heated gases from the exhaust of an internal combustion engine through said tubes, and a baffle plate supported within said casing, whereby the explosive mixture will be carried in contact with the flanged tubes and through said casing.
- 15 2. A gaseous mixture heater comprising an elongated flattened casing having flanges on its flattened portion adapted to be secured to the adjacent flanges of the carbureter and the intake manifold, said casing having oppositely disposed openings to register with the openings through
- 20
- 25
- 30

said intake and said carbureter, an orificed end wall, tubes supported in the orifices in said end wall, a plurality of flange-like rings assembled on said tubes, an end plate adapted to support the free ends of said tubes, a closure cap adapted to be secured to the end wall of said casing, and a closure provided with a plurality of split sockets adapted to be secured to the end of the casing provided with the orificed plate.

3. A heater for gaseous fuel, comprising parallel tubes having their interiors connected at one end forming a passage for exhaust gases from an internal combustion engine, a casing inclosing the parallel portions of the tube having an inlet and an outlet opening for the passage of gaseous fuel through the casing, and baffle plates interposed between the inlet and outlet openings and the tubes, each of said baffle plates having a central conical portion formed with an opening in its apex.

In witness that we claim the foregoing we have hereunto subscribed our names this 19th day of June, 1913.

JAMES S. CONWELL.
HOMER E. HITTLE.
